UNITED STATES PATENT OFFICE.

ROBERT J. HARRY, OF MUNHALL, AND CHARLES S. PROUDFOOT, OF JOHNSTOWN, PENNSYLVANIA.

CRANE TROLLEY.

Application filed May 14, 1926. Serial No. 381,381.

To all whom it may concern:

Be it known that we, ROBERT J. HARRY and CHARLES S. PROUDFOOT, citizens of the United States, and residents of Munhall, Allegheny County, Pennsylvania, and Johnstown, Cambria County, Pennsylvania, respectively, have invented certain new and useful Improvements in Crane Trolleys, of which the following is a specification.

10 This invention relates to a crane trolley, and particularly to a trolley having thereon both main and auxiliary hoists.

Previous types of trolleys having both main and auxiliary hoists have nevertheless 15 been subject to marked disadvantages.

These have arisen largely from the fact that the auxiliary hoist has either been fixed relatively to the main hoist or has been movable at right angles to the main hoist. In 20 such cranes, it has been possible to utilize the auxiliary hoist in tipping ladles and the like from but one side thereof, and at but one of the extreme limits of travel of the main trolley.

25 One object of the present invention is, therefore, to provide a crane trolley having both main and auxiliary hoist, in which the auxiliary hoist is capable of tipping ladles, or of being attached to articles to be handled, from either side thereof and at both 30 extreme limits of travel of the main hoist.

Another object of the invention is to provide a crane trolley having both main and auxiliary hoists, in which the hoisting cables 35 of both hoists lie between the two crane girders, thus permitting the placing of foot-walks or the like on the outside of both girders.

In the accompanying drawings, Figure 1 40 is an end elevation of the crane trolley of the present invention.

Figure 2 is a side elevation thereof.

Figure 3 is a plan view of the trolley.

The crane trolley of the present invention 45 comprises primarily the main hoist 1, having truck wheels 2 which run upon rails 3 on the crane girders 4, and the auxiliary hoist 5, which is mounted on truck wheels 6 which run upon the rails 7 lying longitudinally of the main hoist and supported on the girders 8 of the frame of the main hoist.

The hoisting cables 9 of the main hoist 50 pass over suitable pulleys in main bridles 10 and in the frame of the main hoist, and around the main hoisting drum 11 which

is mounted on a shaft 12, in the frame of the main hoist.

The auxiliary hoisting cables 13 pass over suitable pulleys 14 in the auxiliary bridles 15 and in the frame of the auxiliary hoist 60 and around the auxiliary hoisting drum 16 on a shaft 17 journaled in the frame of the auxiliary hoist 5.

It will be noted that the auxiliary hoist 5 is so positioned that it lies wholly between 65 the cables 9 of the main hoist, and can therefore travel the entire longitudinal extent of the main hoist without interference from the main hoisting cables.

The means for actuating the main hoisting 70 drum 11 comprise an electric motor 18 and suitable speed reducing connections from the motor to the hoisting drum. Such connections comprise a pinion 19 on the motor shaft, a gear 20 on a shaft 21 and meshing 75 with the pinion 19, a pinion 22 on shaft 21 and meshing with a gear 23 on a second shaft 24, and a pinion 25 on shaft 24 and meshing with a gear 26 on the hoisting drum 11.

The means for causing longitudinal travel of the main hoist 1 comprise an electric motor mounted in the frame of the main hoist 1, and suitable actuating connections from this motor to the truck wheels 2 of the 85 main hoist.

A pinion 28, on the shaft of motor 27 meshes with a gear 29 on a shaft 30, which extends the complete width of the main hoist and is journaled in the frame thereof. On shaft 30, adjacent its extremities, are pinions 31 which mesh with gears 32 mounted on short shafts 33 which are journaled in the frame of the main hoist. Gears 32 mesh with large gears 34 on the 95 axles 35 of the truck wheels 2.

This arrangement of actuating connections is such that power is transmitted to the wheels of the main hoist without in any way obstructing the clear space within 100 the side members or frame of the hoist. The auxiliary hoist is thus free to move to either extreme limit of the main hoist.

The means for actuating the auxiliary hoisting drum 16 comprise an electric 105 motor 36 and suitable speed reducing connection from the motor to the hoisting drum. Such connections comprise a pinion 37 on the motor shaft and meshing with a gear 38 on a shaft 39, which is journaled 110.

in the frame of the auxiliary hoist and extends transversely the width thereof. On this shaft 39 is a pinion 40 meshing with a gear 41 on the auxiliary hoisting drum 16.

- 5 The means for propelling the auxiliary hoist 5 longitudinally of the main hoist 1 comprise an electric motor 42, and suitable connections to the truck wheels 6 of the auxiliary hoist. Such connections comprise 10 a pinion 43 on the shaft of motor 42, which meshes with a gear 44 on the transverse shaft 45, and on shaft 45 is a pinion 46 meshing with a gear 47 on the shaft of axle 48 of the truck wheels 6.

- 15 It will be seen that the auxiliary hoist of the trolley is self propelled and self contained. Its arrangement on the main hoist and the arrangement of the actuating and hoisting means and connections of the main 20 hoist, permit it to move longitudinally of the main hoist from one extreme limit to the other thereof. The auxiliary hoist may thus be utilized to tip ladles from either side thereof, or its hoisting cables may be attached to either side of an article to be 25 handled.

The arrangement of the trolley is such that the hoisting cables of both the main and auxiliary hoist depend between the 30 girders of the crane in connection with which the trolley is employed. Free space is thus left on both sides of the trolley for foot walks and for the mounting of the bridge traversing motor of the crane.

- 35 Other advantages of the invention will be apparent to those skilled in the art to which the invention appertains, and as it is susceptible of a number of modifications without departing from the spirit of the invention, no limitations, other than those contained in the appended claims are to be imposed.

We claim:—

1. The combination with a traveling crane, having a self propelled main hoist adapted to travel lengthwise of said crane, said hoist comprising a wheeled frame, and having suitable hoisting cables trained over and depending from suitable pulley sheaves journaled at each side of said frame, of a self 45 propelled auxiliary hoist supported on and adapted to move longitudinally of said main hoist, said auxiliary hoist comprising a wheeled frame adapted to travel upon a pair of rails supported on the side girders 50 of the frame of said main hoist, a hoisting drum journaled in said frame of said auxiliary hoist, hoisting cables trained around said drum and over suitable pulley sheaves in said frame and in the hoisting bridle, and 55 means mounted on said auxiliary hoist for operating said drum.

2. The combination with a traveling crane, having a self propelled main hoist adapted to travel lengthwise of said crane, said hoist 65 comprising a wheeled frame, and having suitable hoisting cables trained around a hoisting drum and over suitable pulley sheaves journaled at each side of said frame, of a self propelled auxiliary hoist supported 70 on and adapted to move longitudinally of said main hoist, said auxiliary hoist comprising a wheeled frame adapted to travel upon a pair of rails supported on the side girders of the frame of said main hoist, a 75 hoisting drum journaled in said frame of said auxiliary hoist, hoisting cables trained around said drum, and a motor mounted on said auxiliary hoist adapted to operate said drum.

In witness whereof, we have hereunto signed our names.

ROBERT J. HARRY.
CHARLES S. PROUDFOOT.
